BOMB RACK MAGAZINE WITH RELEASE
MECHANISMJoseph C. Cantley, Beverly, Mass., assignor to
United Shoe Machinery Corporation, Flemington, N. J., a corporation of New Jersey

Application May 31, 1944, Serial No. 538,108

9 Claims. (Cl. 89—1.5)

1

This invention relates to magazines from which articles may be released from aircraft and is illustrated as embodied in a flare magazine, although it should be understood that the magazine is as well adapted to carry other objects such as bombs and the like.

One of the objects of the present invention is to provide a magazine in which a plurality of flares or the like are supported one above another and in which improved mechanism is provided for so supporting the flares and for releasing them from the magazine. As illustrated herein and in accordance with a feature of the invention, the flares are arranged in superposed relation in two rows supported by arms underlying the flares which are held thereby against vertical walls of the magazine. The arms are retracted to release flares alternately from the two rows by mechanism controlled by the operator.

In accordance with another feature of the invention the retraction of the supporting arms is effected by springs, the arms being locked in flare-supporting positions by latches which are engaged by pawls when the magazine is loaded. A vertical shaft provides means for lifting the pawls out of engagement with the latches thereby to permit retraction of the supporting arms according to a predetermined sequence upon rotation of the shaft.

Another feature of the invention relates to the provision of improved mechanism for indexing the shaft. As illustrated herein the shaft carries a segment having teeth spaced around the shaft and axially thereof, the shaft being held in one of a plurality of positions, as determined by the number of teeth on the segment, by a rack having a corresponding number of teeth arranged in the form of steps. This rack is journaled on a shaft parallel to the axis of the indexing shaft and is urged toward locking position with respect to the segment by a spring. The rack carries a set of ratchet teeth engaged by a pawl which is reciprocated to move the rack in small increments upon successive energizations of a solenoid to which the pawl is connected whereupon a spring, acting upon the main indexing shaft, causes this shaft to move a step at a time.

A still further feature of the invention relates to mechanism by which control is automatically transferred from one magazine to another after the first magazine has been completely emptied of its flares so that without any extra effort on the part of the operator the dropping of flares from the second magazine may be effected after the first magazine is completely emptied. As

2

illustrated herein, a switch by which control is transferred from one magazine to another, is automatically closed upon deenergization of the solenoid after the last flare has been released from the magazine. An arm operated by the solenoid moves toward and from the button of the switch but in spaced relation thereto and the rack by which the indexing of the shaft is effected moves a plunger in the path of movement of the arm after the last flare has been released so that through this plunger the switch is closed automatically at the proper time.

The above and other features of the invention, including various details of construction and novel combinations of parts, will now be described in connection with the drawings and pointed out in the claims.

In the drawings,

Fig. 1 is a view partly in section and partly in elevation of one form of magazine embodying the invention;

Fig. 2 is a section on the line II—II of Fig. 1;

Fig. 3 is an end view of the magazine fully loaded, with the end plate removed;

Fig. 4 is a side elevation partly in section of the handle and associated mechanism for resetting the latches by which the flare supports are held in operative positions.

Fig. 5 is a section on the line V—V of Fig. 4;

Fig. 6 is a plan view of the mechanism by which the shaft which controls the position of the latches is indexed;

Fig. 7 is a plan view of a portion of the mechanism shown in Fig. 6 showing the parts in the positions assumed after the magazine has been emptied of flares;

Fig. 8 is a section on the line VIII—VIII of Fig. 6;

Fig. 9 is a detail of a portion of the mechanism for operating the switch by which another magazine is rendered operative after the magazine shown herein has been emptied, this view being taken along the line IX—IX of Fig. 6;

Fig. 10 is an angular view of a portion of the indexing mechanism for operating the latch release shaft;

Fig. 11 is an elevation partly in section of a portion of the latch release shaft and associated mechanism;

Fig. 12 is an elevation partly in section of some of the flare-supporting means and release mechanism including the latch release shaft of Fig. 11;

Fig. 13 is a vertical section of a portion of the mechanism shown in Fig. 12 with the parts in the positions assumed after release of the flares;

Fig. 14 is a side elevation of one of the flare-supporting arms;

Fig. 15 is a front elevation of the handle for moving one of the flare-supporting arms into operative position;

Fig. 16 is a detail view of a portion of one of the latch assemblies;

Fig. 17 is a view similar to Fig. 16 taken at right angles thereto, and

Figs. 18 to 20 are sections taken through the latch release shaft at different portions thereof showing the parts in the positions assumed when the magazine is fully loaded.

The magazine is illustrated in Figs. 1 and 3 as comprising a cylindrical container 10 having end plates 12, 14 and two sets of doors 16, 18 in the under side thereof. These doors are hinged at 20 and are normally maintained in closed positions by light springs (not shown) but open upon engagement thereof by a flare F to permit egress of the flare from the magazine. Secured to the upper portion of the container are brackets 22 and 24, the first of which may be utilized to suspend the magazine from the bomb rack or shackle in the bomb bay of an airplane with the longitudinal axis of the container inclined at 45° to the vertical. The bracket 24 permits the magazine to be suspended vertically from the wing of an airplane. Circular flanges 26 project outwardly from opposite ends of the magazine to permit the attachment of nose and tail fairings when the magazine is suspended from the wing thereby to minimize air resistance.

The container is reinforced by longitudinally extended struts 28 in the sides thereof, a strut 30 along the top and a strut 32 (Fig. 1) in the bottom. Secured to the struts 28 are vertical bars 34 forming the outer walls of a pair of flare compartments. A central partition or wall 36 divides the container and completes the compartments for the flares. As illustrated in Fig. 3, each compartment is designed to hold three flares F in superposed relation but it will be understood that the magazine may be designed to contain any desired number thereof.

For holding the flares in the magazine, a pair of supporting arms 40 is arranged for engagement with the under side of each flare thereby to support the flare in engagement with the outer wall 34 of the compartment. These arms are secured to shafts 42 journaled in the central wall 36, the shafts being urged in directions to retract the arms within the confines of the wall 36 by torsion springs 44 (Figs. 1 and 15) which surround the shafts at their outer ends and act between the wall 36 and handles 46 secured to the shafts. These handles facilitate movement of the shafts against the force exerted by the springs when the magazine is being loaded thereby to move the supporting arms 40 from the retracted positions shown in Fig. 13 into their operative flare-supporting positions as shown in Fig. 14.

For holding the supporting arms in their operative positions against the action of the torsion springs 44, the shafts 42 near their central portions carry latches 50 (Figs. 11, 12 and 13) engageable with pawls 52 carried by pins 54 supported by brackets 56 in the central partition. Springs 58 secured to the pawls 52 normally maintain them in locking engagement with the latches 50 as shown in Fig. 12. When these pawls are swung upwardly out of engagement with the latches 50, the shafts 42 are turned by the torsion springs to retract the arms 40 and permit the flares to drop through the lower portion of the

magazine. It will be understood that each pair of arms 40 is carried by a separate shaft 42 and each of these shafts carries a latch 50 for which there is provided a locking pawl 52.

For moving the pawls out of locking engagement with the latches 50 a vertical, centrally located shaft 60 is journaled in the partition 36. This shaft carries three spools 62, 64, 66 (Fig. 1). The spool 62 controls the pawls 52 which operate on the lowermost shafts 42, the spool 64 controls the pawls associated with the intermediate shafts 42 and the spool 66 controls the pawls associated with the uppermost shafts 42. As shown in Fig. 18 the spool 62 includes a cam 68 provided in its periphery with a pair of recesses 70, 72 in which are positioned the lower ends of arms 74 (Fig. 16) integral with the pawls 52. The spool 62 is shown in the position assumed when the magazine is completely loaded and the supporting arms 40 are all in their flare-supporting positions. Upon movement of the shaft 60 in a counterclockwise direction as viewed in Fig. 18, the shoulder 76 formed by the recess 70 engages the adjacent arm 74 thereby to rock it in a clockwise direction as viewed in Fig. 12, moving the pawl 52 out of engagement with the latch 50 whereupon the flare at the lower right hand corner in this figure is released and drops from the magazine. The shaft 60 is moved in a step-by-step manner in a counterclockwise direction by mechanism to be described so that the flares are released one at a time. It will be noted that the recess 72 in the cam 68 is of a greater peripheral length so that further movement in a counterclockwise direction of the spool 62 is required before the associated arm 74 is moved to release the pawls controlling the shaft 42 adjacent to the one which has been previously released. The spools 64 and 66 shown in Figs. 19 and 20 respectively are provided with similar recesses but of progressively increasing lengths so that upon successive movements of the shaft 60 the arms 74 are successively operated to release flares alternately from one side of the magazine and the other starting with the lowermost flares and ending with the uppermost flares.

After the pawls have been moved upwardly to release the latches 50 they are locked in their upper positions by the engagement of pins 80 with the upper surfaces of flanges 82 or 84 on the spools, the flanges being provided with recesses 86 to receive the pins 80 when the pawls are in engagement with the latches on the shafts 42 as shown in Figs. 16 and 18 to 20. After the spool has been turned sufficiently to move one of the arms 74 to release its associated shaft 42 the pin 80 moves out of the recess 86 in the adjacent flange and upon slight further movement of the shaft 60 the recess moves away from the pin and the flange accordingly locks the arm 74 in its upper position as indicated by the broken lines in Fig. 16. As shown in Figs. 18, 19 and 20, the recesses in the flanges starting from the lowermost one of the lowermost spool and ending with the uppermost flange of the top spool are of increasing peripheral lengths so that each pin may remain in its recess until the arm by which it is carried is swung upwardly after which the arm is locked in its upper position. From the above it will be seen that as the shaft 60 is turned in a counterclockwise direction as viewed in Fig. 18 the cams 68 cause release of the latches 50 in a predetermined order whereupon the flare supports 40 are moved by the springs 44 into the confines of the partition 36 as indicated in Fig. 13 permitting release of the flares from the con-

tainer. After each flare has been released the pawl controlling its release is locked in its inoperative position by engagement of the pin 88 carried by the arm 74 with one or the other of the flanges in the adjacent spool.

Secured to the shaft 60 is a pair of torsion springs 88 secured at their upper ends by collars 90 pinned to the shaft 60 and at their lower ends to pins 92 carried by the partition 36. These springs are arranged to rotate the shaft 60 in a direction to release the flare supports, and to control the movement of the shaft by these springs an escapement mechanism 94 (Fig. 10) is provided. This mechanism includes a disk 96 secured to the upper end of the shaft 60 and carrying a release segment 98 provided with teeth 100 in the form of steps concentrically disposed around the shaft. This segment cooperates with a rack 102 depending from an arm 104 journaled on a shaft 106 carried by the strut 30 and extending parallel with the shaft 60. The rack 102 is provided with steps 108 complementary to the steps 100 of the segment 98 so that as the rack 102 is moved about the shaft 106 in a counterclockwise direction as viewed in Fig. 10 in a step-by-step manner, it will permit movement of the disk 96 and consequently of the shaft 60 in a counterclockwise direction in a step-by-step manner, the increment of movement depending upon the lengths of the steps 100 of the segment. Movement is imparted to the rack 102 by a solenoid 110 (Fig. 6) the armature of which is connected by a link 112 to a lever 114 pivoted on a pin 116 carried by the strut 30, this lever being connected to a pawl 118 held by a spring 120 in engagement with a ratchet 122 on the arm 104. Upon each energization of the solenoid the ratchet is moved through the above-described connections in a counterclockwise direction a sufficient distance to permit the shaft 60 to turn one step under the influence of the springs 88 to release a flare from the magazine. The rack 102 is held in engagement with one of the steps 108 of the segment 98 depending upon the position of the rack, by a spring 124 connected between a pin 126 on the rack and a pin 128 carried by the strut 30. The stroke of the armature of the solenoid 110 is just sufficient to cause the shaft 60 to be turned far enough to release one flare so that upon each energization of the solenoid a flare is released from the magazine until the magazine is entirely empty of flares.

It may be desirable to mount two or more magazines of the type described herein on a single plane and to place all magazines under the control of the operator so that after one magazine is emptied a circuit is automatically established to the solenoid of another magazine and no separate operation on the part of the operator is required to place a second magazine under the control of the switch by which the solenoid is operated. A switch 130 for placing the solenoid of an additional magazine under the control of the operator is mounted in the strut 30 and is arranged to be closed automatically by the following mechanism after the magazine has been emptied. Pivoted on a pin 132 (Fig. 9) supported by a bracket 133 carried by the strut 30 is an upwardly extending arm 134 having at its upper end a horizontal extension 136 disposed in the path of movement of the forward edge of the ratchet 122. The arm 134 is normally held in a vertical position as shown in Fig. 9 by a spring 138, the arm being provided with a downwardly extending projection 140 engageable with a shoul-

der on the bracket 133 thereby to limit the movement of the arm under the influence of the spring 138. After the magazine has been emptied of flares the ratchet 122 assumes the position shown in Fig. 7 and by its engagement with the upper end 136 of the arm 134 moves this arm into the broken line position of Fig. 9. The upper end of the arm carries a slidable pin 142 which moves into alignment with a disk 144 at the rear end of a rod 146 which is aligned with a button 148 of the switch 130 when the arm 134 is in the broken line position of Fig. 9. The lever 114 through which motion is imparted to the pawl 118 by the solenoid 110 includes an extension 150 engageable with the rearward end of the pin 142 after the pin has moved into register with the disk 144. Consequently after the ratchet 122 has reached the limit of its movement at which time the magazine is emptied of flares, the pin 142 assumes a position between the end 150 of the lever 114 and the disk 144. Upon deenergization of the solenoid 110, the lever 114 is returned to the position shown in Fig. 6 by a spring (not shown) acting on the armature of the solenoid and by engagement of the end of the lever 114 with the pin 142 moves the pin to the left which in turn moves the rod 146 to the left and actuates the switch button 148 thereby to close the circuit controlled by the switch 130 and to place another magazine under the control of the operator.

In order to reload the magazine it is necessary to turn the shaft 60 back to its original position thus energizing the springs 88 and returning the spools, carried by the shaft, into positions in which the pawls 52 may engage the latches on the shafts 42 when the supports 40 are moved into operative positions. For thus operating the shaft 60 a handle 154 (Figs. 1, 4 and 5) is provided. This handle is located just below the lower strut 32 and is pivoted at 156 to a sleeve 158 which is in turn secured by a pin 160 to a circular shank 162 depending from a disk 164 resting on the upper portion of the strut 32. The disk 164 carries an upwardly extending projection 166 arranged for engagement with a depending projection 168 of a collar 170 secured to the lower end of the shaft 60 thereby to transmit motion from the handle to the shaft. When the magazine is fully loaded the members 166 and 168 are spaced as indicated in Fig. 5 but as the shaft 60 turns in a counterclockwise direction during the flare releasing operation, the member 168 moves toward the member 166 and engages it as the last flare is released.

The handle 154 is normally locked in the position shown in Figs. 1 and 4 by a slide 172 (Figs. 2 and 4). This slide comprises a pair of longitudinally extending bars interconnected by a pin 174 and guided for longitudinal movement along the strut 32 by bolts 176 which pass through slots 178 in the slide. These bolts also serve to secure together the bars comprising the slide. The slide is normally held in either one of two positions by a spring-pressed detent 180 engageable with spaced recesses 182 in the slide. The slide includes an inwardly extending plate 184 having an angular projection 186 receivable in a slot formed in the lower end of the sleeve 158 as shown in Fig. 4 so that when the slide is in the position illustrated it acts to lock the sleeve and shaft against rotation. At this time the handle is held against the under surface of the strut 32 by engagement of the extension 186 with a surface 188 of the handle. However, when the slide is moved to the left the projection 186 moves out of engage-

ment with the handle and out of the slot in the lower end of the sleeve 158 whereupon the handle drops sufficiently to enable it to be conveniently grasped by the operator and the sleeve 158 is free to be rotated.

The slide also retracts the pawl 118 to free the ratchet 122 for movement with respect thereto when the parts are reset. For this purpose the pawl is provided with a cam surface 190 (Fig. 8) arranged for engagement by a pin 192 carried by one end of an arm 194 the other end of which is pivoted on a pin 196 on a bracket 198 extending upwardly from the strut 30. Upon moving the arm 194 downwardly about the pivot 196 the pin 192 acts on the cam surface 190 to move the pawl against the force of the spring 120 out of engagement with the ratchet 122. The arm 194 is normally held in the position shown in Fig. 8, with the pin out of engagement with the cam surface 190, by a link 200 the lower end of which is connected to a bell crank lever 202 (Fig. 1) pivoted at 204 to a bracket carried by the central partition. This bell crank lever carries a pin 206 engageable with a surface 208 on the slide 172 so that when the handle 154 is locked by the slide the pawl 118 is held in engagement with the ratchet 122 by the spring 120. Upon movement of the slide 172 to the left to free the handle for resetting the shaft 60, the pin 206 in the bell crank lever 202 drops off the surface 208 and the pin 174 engages a downward projection of the bell crank lever thereby positively moving it in a clockwise direction as viewed in Fig. 1, transmitting motion through the link 200 to pull the arm 194 (Fig. 8) downwardly thus camming the pawl out of engagement with the ratchet. Consequently, as the shaft 60 is reset and the segment 98 (Fig. 10) is returned to the position shown in Fig. 10, the spring 124 permits return of the rack 102 and with it the ratchet 122 thereby returning the parts to the positions illustrated in Fig. 10.

In reloading the magazine the doors at the bottom of the container are opened to permit the insertion of flares therethrough and upon moving each flare into position with respect to the supports 40, the handle 46 for moving each pair of supports is operated to carry the supports into engagement with the flares as shown in Fig. 3, at which time the supports are locked in position by engagement of the pawls 52 with the latches 50. It will be understood that if the shaft 60 has not been properly reset the pawls 52 will be held in their raised positions by engagement of the pins 80 with the upper surfaces of the disks carried by the respective spools and consequently it is impossible to reload the magazine if the shaft 60 has not been returned to its original position and the springs 28, for operating the shaft, have not been energized. The lanyards carried by the flares are inserted through holes in one of the end plates 12, 14 and the ring at the end of the lanyard is hooked against the outer surfaces of the end plates by hinged lanyard plates 210 (Fig. 1). After the magazine is fully loaded the slide 172 is moved to the right, locking the handle in the position illustrated in Figs. 1 and 4 and permitting the pawl 118 to be moved into engagement with the ratchet 122, the doors 16 and 18 at the bottom of the container are permitted to close and the magazine is ready for operation.

Having thus described the invention, what I claim as new and desire to secure by Letters Patent of the United States is:

1. An aircraft flare magazine comprising means

for supporting a plurality of flares in superposed relation, means urging said supporting means into inoperative positions, latches for holding said supporting means in operative positions, a latch

5 release shaft, means carried by said shaft for causing successive release of said latches in response to successive turning movements of said shaft, means for operating said shaft, and means carried by said shaft for maintaining said latches 10 in inoperative positions until said shaft has returned to an initial position.

2. An aircraft flare magazine comprising a container, walls forming a compartment in said container for flares supported in superposed relation 15 therein, means carried by one of said walls for supporting said flares, means carried by said wall for locking said supporting means in operative positions, a rotatable shaft carried by said wall, means carried by said shaft for successively releasing said locking means in response to rotative movement of said shaft to permit sequential release of said flares from the container, and means for turning said shaft in a step-by-step manner.

3. An aircraft flare magazine comprising a container, walls forming a compartment in said container for flares supported in superposed relation therein, means carried by one of said walls for supporting said flares, means carried by said wall for locking said supporting means in operative positions, a rotatable shaft carried by said wall, means carried by said shaft for successively releasing said locking means in response to rotative movement of said shaft to permit sequential release of said flares from the container, a spring 35 acting on said shaft tending to turn it in a direction to release said means, mechanism for locking said shaft in any one of a plurality of positions, and means for successively operating said locking means to permit movement of said shaft by the 40 spring in a step-by-step manner.

4. An aircraft flare magazine comprising a container, walls forming a compartment in said container for flares supported in superposed relation therein, a plurality of horizontal shafts journaled 45 in one of said walls in vertically spaced relation, arms carried by said shafts for supporting flares in the compartment, means acting on said shafts to carry the arms into retracted positions, latches carried by said shafts, pawls carried by said wall for engagement with said latches to lock the shafts with the arms in operative positions, a vertical shaft, means carried by said vertical shaft for successively releasing said pawls in response to rotation of said shaft, and means for imparting 50 step-by-step rotative movement to said shaft.

5. An aircraft flare magazine comprising a container, walls forming a compartment in said container for flares supported in superposed relation therein, a plurality of horizontal shafts journaled 60 in one of said walls in vertically spaced relation, arms carried by said shafts for supporting flares in the compartment, means acting on said shafts to carry the arms into retracted positions, latches carried by said shafts, pawls carried by said wall for engagement with said latches to lock the shafts with the arms in operative positions, a vertical shaft, means carried by said vertical shaft for successively releasing said pawls in response to rotation of said shaft, means for imparting 65 step-by-step rotative movement to said shaft, and means carried by said shaft for holding said pawls in inoperative positions until the vertical shaft has returned to an initial position.

6. In combination, a shaft, a spring acting on 70 said shaft to turn it, a segment carried by said

shaft having teeth spaced around the shaft and lengthwise thereof, a rack having teeth cooperating with the teeth on said segment for locking the shaft against movement by said spring in any one of a plurality of positions, means mounting said rack for a pivotal movement about an axis parallel to the axis of rotation of said shaft, means urging said rack into locking engagement with the said segment, and means for moving said rack in a step-by-step manner to permit step-by-step movement of said shaft.

7. In combination, a shaft, a spring acting on said shaft to turn it, a segment carried by said shaft having teeth spaced around the shaft and lengthwise thereof, a rack having teeth cooperating with the teeth on said segment for locking the shaft against movement by said spring in any one of a plurality of positions, means mounting said rack for a pivotal movement about an axis parallel to the axis of rotation of said shaft, means urging said rack into locking engagement with the said segment, means for moving said rack in a step-by-step manner to permit step-by-step movement of said shaft, a ratchet carried by said rack, a pawl engageable with said ratchet, means for reciprocating said pawl thereby to move the rack relatively to the segment and permit step-by-step movement of said shaft, means for turning said shaft against the force exerted by the spring, means for locking said shaft turning means, and means operative in response to the unlocking of the shaft turning means for holding said pawl out of engagement with said ratchet.

8. An aircraft flare magazine comprising means for supporting a plurality of flares in superposed relation, means mounting said supporting means for movement into and out of operative positions, a vertical shaft having means for successively releasing said supporting means for movement into inoperative positions, a spring acting on said shaft to turn it in a direction to release said supporting means, a segment carried by said shaft having teeth spaced therearound and lengthwise thereof, a rack having teeth cooperating with the teeth on said segment for locking the shaft against movement by said spring in any one of a plurality of positions, means mounting said rack for pivotal movement about an axis parallel to the axis of rotation of said shaft, means urging said rack into locking engagement with the said segment, and means for moving said rack in a step-by-step manner to permit step-by-step movement of said shaft.

9. An aircraft flare magazine comprising means for supporting a plurality of flares in superposed relation, means mounting said supporting means for movement into and out of operative positions, releasable means for holding the supporting means in operative position, a vertical shaft having means for successively releasing said holding means to permit movement of the supporting means into inoperative positions, a spring acting on said shaft to turn it in a direction to release said holding means, a segment carried by said shaft having teeth spaced therearound and lengthwise thereof, a rack having teeth cooperating with the teeth on said segment for locking the shaft against movement by said spring in any one of a plurality of positions, means mounting said rack for pivotal movement about an axis parallel to the axis of rotation of said shaft, means urging said rack into locking engagement with the said segment, a ratchet carried by said rack, a pawl engageable therewith, means for reciprocating the pawl thereby to move the rack relatively to the segment and permit step-by-step movement of said shaft, means for turning said shaft against the force exerted by the spring to permit resetting said supporting means, means for locking said shaft-turning means, and means operative in response to unlocking of said shaft-turning means for holding the pawl out of engagement with said ratchet.

JOSEPH C. CANTLEY.
